UNITED STATES PATENT OFFICE.

ALFRED S. DONALDSON, OF NEWARK, NEW JERSEY, ASSIGNOR TO DU PONT VISCOLOID COMPANY, OF WILMINGTON, DELAWARE, A CORPORATION OF DELAWARE.

DESIGN FOR A TOILET BOX.

Application filed February 12, 1927. Serial No. 20,719. Term of patent 7 years.

To all whom it may concern:

Be it known that I, ALFRED S. DONALDSON, a citizen of the United States, and a resident of Newark, in the county of Essex and State of New Jersey, have invented a certain new, original, and ornamental Design for a Toilet Box, of which the following is a specification, reference being had to the accompanying drawing, forming part thereof.

In the drawing Figure 1 is a perspective view of a toilet box, showing my new design; and Figure 2 is a top view of such box.

I claim:

The ornamental design for a toilet box, as shown.

In testimony whereof I affix my signature.
ALFRED S. DONALDSON.
